UNITED STATES PATENT OFFICE

LESTER L. COLLINS, OF FRANKLIN, PENNSYLVANIA, ASSIGNOR TO CHICAGO PNEUMATIC TOOL COMPANY, OF NEW YORK, N. Y., A CORPORATION OF NEW JERSEY

AUTOMATIC REGULATOR FOR COMPRESSORS

Application filed June 4, 1931. Serial No. 542,080.

This invention relates to fluid compressors or pumps, more particularly air and gas compressors, the output of which is usually varied automatically in response to the demands upon the receiver into which the compressed fluid is discharged. In the interests of economy and efficiency such machines are arranged to load and unload in a plurality of steps or stages. In certain aspects the invention may 5 be considered an improvement upon or further development of the control apparatus disclosed and claimed in U. S. Patent No. 1,685,781 issued October 2, 1928 to Leon F. Hoffman.

15 Among the objects of the present invention are to devise a regulator which operates positively under slight changes in pressure, to produce a simplified design of regulator having a reduced number of working parts, and 20 in general to simplify and to improve prior apparatus of this character.

In the present invention the compensating mechanism by which exact regulation in stages is secured involves an oscillating cam which 25 is connected directly to the power piston of conventional fluid pressure control apparatus such as a Mason regulator. The movement of the cam can then be made to correspond directly with the movement of the distributing piston which is also directly connected to the power piston. If proportional rather than substantially the same movement is required, this is easily accomplished by running 30 the connection from the power piston to the lever arm of the oscillating cam rather than to the cam itself. In any case the cam can be arranged directly above the power cylinder thereby producing a very compact and exceptionally simple construction.

40 In order to illustrate the invention, one concrete embodiment thereof is shown in the accompanying drawings, in which:

Fig. 1 is a plan view of the control unit;

Fig. 2 is a side elevational view of the parts 45 shown in Fig. 1 on an enlarged scale and with certain portions shown in vertical section; and

Fig. 3 is a fragmentary horizontal sectional view substantially on the line 3—3 of Fig. 2.

The embodiment of the control unit or 50 fluid pressure governor chosen for the pur-

pose of illustration comprises a support 4 which may be mounted adjacent to or directly upon the variable volume compressor or other machine to be controlled and may be suitably connected to a source of fluid pressure, such as the receiver of the machine to be controlled. Secured to support 4 is a casing 5, the support and the casing together providing a chamber 6 in which is disposed a diaphragm 7, the lower face of which is subjected to fluid pressure through opening 8. Movement of diaphragm 7 under the pressure of the motive fluid acts through a saddle member 9 resting upon or secured to the diaphragm upon a lever arm 10 pivoted at 11 and provided at its outer end with weights 12. Movement of lever 10 is transmitted through a yoke or other connection 13 to an arm or link 14 from which is suspended a fluid control or pilot valve 15 of the well-known Mason regulator type controlling passages 16 and 17 leading to opposite ends of a chamber provided by a cylinder 18 in which reciprocates a piston 19. The fluid controlled by valve 15 may be water under pressure. Piston 19 is connected on the exterior of cylinder 18 by a head 20 and rod 21 to a balanced or double-headed piston 22 movable in a cylinder 23 adjacent to and in parallelism with cylinder 18 (Figs. 1 and 3). The space 25 between the heads of piston 23 is always in communication with receiver pressure through an inlet pipe 24. Movement of piston 23 to the left (Fig. 3) serves to connect to receiver pressure in succession pipes 25, 26, 27 and 28 which lead to the unloading devices (not shown) in the compressor, pump or other machines to be regulated. The arrangement shown is for the so-called five-stage regulation whereby with the parts in the position illustrated in Fig. 3, the compressor is operating on full load. Movement of piston 22 to the left will produce quarter unloading with the opening of pipe 25 to receiver pressure, half-unloading when pipe 26 is opened, three-quarter unloading with the opening of pipe 27 and total unloading with the opening of pipe 28. A vent opening at 30 pipe 29 serves to relieve the pressure in pipes 35 100

28, 27, 26 and 25 in succession when piston 22 moves to the right.

In order to insure that the movement of pistons 19 and 23 shall be controlled in well defined steps to produce the progressive stages of unloading and loading of the compressor, compensating means are provided quickly to restore pilot valve 15 to neutral position after each movement. To this end 10 a rod 30 extends from head 20 and connects directly to a cam arranged for rocking movement through an arm 32 which is pivoted at 33 at the base of cylinder 18. The control surface of cam 31 is slightly arcuate and 15 has a series of irregular depressions, four in number, corresponding to the extent of movement of distributing piston 22 necessary to contact pipes 25-28 inclusive in succession to receiver pressure. Arm 32 extends 20 radially of the control surface as clearly indicated in Fig. 2. A roller 34 mounted on one end of a lever 35 is maintained in contact with the arcuate control surface of cam 31 through the action of a spring 36. Lever 25 35 is pivoted at its center to a bracket 37 mounted upon the top of cylinder 18 and the end of the lever remote from roller 34 is pivoted to link 14 carrying pilot valve 15.

It will be clear that when the fluid pressure against diaphragm 7 becomes sufficient 30 to overcome weights 12, lever 10 moves upwardly carrying with it the yoke 13 and link 14 thus lifting pilot valve 15 which thereupon admits water to passage 16 and opens 35 a vent for passage 17. In consequence, piston 19 moves to the left and head 20 transmits this movement both to distributor piston 22 and rocking cam 31. When piston 22 moves far enough to admit pressure fluid into 40 pipe 25 roller 34 drops into the first depression in cam 31. Due to the swinging movement of the cam this has the effect of lowering slightly the left end of link 14 so that the pilot valve 15 is moved to neutral position 45 and the control mechanism comes to rest after sufficient movement to effect first stage unloading of the compressor. Upon further increase in pressure in the receiver, the next position of distributing piston 22 is assumed 50 with pipe 26 uncovered to effect second stage unloading of the compressor. Upon further increases in pressure the remaining pipes 27 and 28 are uncovered in succession in an obvious manner. Upon a drop in pressure 55 the unloading steps are retraced in order to effect progressive loading of the compressor. The operating condition of the compressor or other machine which is controlled may be indicated by the position of a pointer 60 p attached to head 20 and moving across a scale s secured to cylinder 18.

The operating range of the governor may be adjusted by applying progressively greater resistance to the rising movement of lever 65 arm 10 as, for example, by a coil spring 38

attached at one end to a collar 39, slideable on lever arm 10 and at the other end to a bolt 40 extending through a slotted support 41 beneath arm 10 and having a stop nut 42 in contact with said support. Resistance to upward movement of lever 10 may obviously be varied either by tightening or loosening nut 42 or by moving the spring assembly longitudinally of lever 10 and support 41.

From the above it will be apparent that the control apparatus of the present invention involves a minimum number of movable parts, that the use of an oscillating or rocking cam disposed immediately above the power cylinder permits a very compact arrangement, and that the connection of the cam directly to the cross head between the power and the distributing piston by a single link permits positive and accurate regulation of the movement of the distributing piston.

While the invention has been herein shown and described in what is now considered to be its preferred form, it is understood that the invention is not to be limited to the specific details thereof, but covers all changes, modifications, and adaptations within the scope of the appended claims.

I claim as my invention:

1. In automatic regulating apparatus for a variable volume compressor, a pilot valve controlled by receiver pressure, a reciprocable piston controlled by said pilot valve, means for returning the pilot valve to neutral position after each movement comprising a cam having a generally arcuate control surface, an arm extending from said cam and radially of said control surface and arranged for swinging or rocking movement about a pivotal point remote from said cam, and a connection between said cam and said piston whereby axial movement of the latter causes rocking movement of the former.

2. A fluid pressure governor for a variable volume compressor comprising a control valve, means for effecting movement of said valve in response to variations in receiver pressure, a power piston controlled by said valve, a control piston adjacent to and in parallelism with said power piston, a head connecting said pistons to effect movement of one with the other, compensating means for restoring said valve to neutral position so as to effect successive stages of movement of said pistons comprising a cam mounted above said power piston for rocking movement, and a connecting rod pivoted respectively to said cam and said head.

3. A fluid pressure governor for a variable volume compressor comprising a weighted arm movable in response to receiver pressure, a pilot valve, a link from which said valve is suspended, a connection for said arm to one end of said link whereby said valve

- is movable in response to movement of said arm, a power piston controlled by said valve, and compensating means for restoring said valve to neutral position after movement
- 5 comprising a cam member having an arcuate cam face, means including a connection to said piston for rocking said cam about a pivot point remote from its cam face, and a lever pivotally supported at its center and
- 10 pivotally connected at one end to the end of said link remote from said weighted arm connection, said lever having a roller on its free end in engagement with the cam face of said cam member.
- 15 4. A fluid pressure governor for a variable volume compressor comprising a pilot valve, means for effecting movement of said valve in response to receiver pressure, a power cylinder adjacent said valve having a piston controlled by said valve, and compensating means for restoring said valve to neutral
- 20 position after each movement mounted upon and above said cylinder including a rockably mounted cam connected by a link to said
- 25 piston.
5. A fluid pressure governor for a variable volume compressor comprising a pilot valve, means for effecting movement of said valve in response to receiver pressure, a power cylinder adjacent said valve having a piston controlled by said valve, and compensating means for restoring said valve to neutral
- 30 position after each movement mounted upon and above said cylinder including a link sup-
- 35 porting said valve, a rockably mounted cam connected to said piston, and a single lever interposed between said cam and said link.

Signed by me at Franklin, in the county of Venango and State of Pennsylvania, this

40 1st day of June, 1931.

LESTER L. COLLINS.
